COMBINED WALL MOUNTED ROOM AIR FRESHENER AND DEODORIZER

Morris Friedman, 210 E. 36th St., New York 16, N.Y., and Andrey V. Mackey, 42 Lawrence Lane, Ambler, Pa.

Filed Apr. 17, 1963, Ser. No. 74,487

Term of patent 14 years

(Cl. D16—2)

FIG. 1 is a front elevational view of a combined wall mounted room air freshener and deodorizer showing our new design;

FIG. 2 is a rear elevational view of the combined wall mounted room air freshener and deodorizer of FIG. 1; and

FIG. 3 is a side elevational view of the combined wall mounted room air freshener and deodorizer of FIG. 1.

We claim:

The ornamental design for a combined wall mounted room air freshener and deodorizer, substantially as shown.
